PICKER STICK CHECK FOR LOOMS

Franklin A. Ritchie, Charlotte, N. C.

Application July 21, 1949, Serial No. 105,919

2 Claims. (Cl. 139—164)

1

This invention relates to a loom and more especially to an improved picker stick check therefor adapted to be secured to the lay, at opposite ends thereof, and having means for frictionally engaging the picker stick upon the shuttle being thrown into the corresponding shuttle box and having other means to release the pressure of the friction means against the picker stick immediately before the picker stick again throws the shuttle out of the corresponding shuttle box and across the lay.

The primary object of this invention is to provide a picker stick check comprising a fixed friction member or check shoe and a spring loaded friction member between which the picker stick is adapted to move upon a shuttle being thrown into a corresponding shuttle box, to thus frictionally hold the picker stick in its outermost position and to prevent the shuttle from rebounding upon moving into the shuttle box.

It is another object of this invention to provide means automatically operable in timed relation to the picking mechanism of the loom, for releasing the picker stick check from engagement with the picker stick to permit the return stroke thereof, said means for releasing the picker stick being controlled by means mounted on the cam shaft of the loom.

It is still another object of this invention to provide means for moving the spring loaded friction means out of engagement with the picker stick immediately before the return stroke of the picker stick, said means comprising a cam wheel fixedly mounted on the cam shaft of the loom and being positioned thereon relative to the conventional picker cam so as to transmit oscillatory motion to a lever arm, in timed relation to movement of the picker stick. This lever arm has one end of a link connected to an outturned portion of a shaft having means on one end thereof for engaging and moving the spring loaded friction member out of engagement with the picker stick in timed relation to movement of the pick cam into engagement with the picker stick operating means for effecting the return stroke of the picker stick as in throwing the shuttle across the lay.

Some of the objects of the invention having been stated, other objects will appear as the description proceeds, when taken in connection with the accompanying drawings, in which

Figure 1 is a longitudinal vertical sectional view through a loom, showing various parts schematically and illustrating the cam controlled means for the picker stick check;

2

Figure 2 is an enlarged top plan view with parts in section taken along the line 2—2 in Figure 1 and showing the cam means and lever associated therewith for controlling the picker stick check;

Figure 3 is an enlarged elevation showing the loom frame in cross section and is taken substantially along the line 3—3 in Figure 1 looking at the back of one of the shuttle boxes of the loom;

Figure 4 is an elevation looking at the front or opposite side of the shuttle box shown in Figure 3 and showing the manner in which the stationary friction member is secured to the front of the shuttle box;

Figure 5 is an enlarged bottom view of the shuttle box with the improved picker stick check applied thereto and with parts in section and is taken substantially along the line 5—5 in Figure 3;

Figure 6 is an enlarged end elevation of the shuttle box looking along the line 6—6 in Figure 3;

Figure 7 is an enlarged vertical sectional view taken along the line 7—7 in Figure 3.

Referring more specifically to the drawings, the numeral 10 indicates the right-hand side frame member of a loom, to the inner surface of which one end of girts 11 and 12 are connected in a conventional manner, the other ends of the girts 11 and 12 being connected to the left-hand side frame member not shown. The present invention is shown in association with the right-hand side of the loom only; however, it is to be understood that a similar apparatus may be mounted at the left-hand side of the loom and an illustration and description of the structure of the left-hand side of the loom is deemed unnecessary.

The loom side frame member 10 also has one end of a conventional arch 14 and a breast beam 15 each connected at one end to the loom side frame member 10. One end of a conventional rocker shaft 16 is oscillatably mounted in the lower portion of the side frame member 10 and has a sword 17 fixedly mounted thereon. The sword 17 extends upwardly and has a lay 20 and a reed cap 21 secured thereto as by bolts 22 and 23, respectively (Figure 3). This particular type of sword 17 has a vertically disposed plate portion 25 integral therewith which is also penetrated by a bolt 26 to further assist in securing the lay 20 to the sword 17.

The sword 17 has a pitman arm shaft 27 fixedly mounted therein to which, in Figure 1, one

end of a conventional pitman arm 30 is oscillatably mounted. This pitman arm 30 extends rearwardly in Figure 1 and is oscillatably mounted on one of the crank throws of a conventional crank shaft 31, one of the ends of which is rotatably mounted in a bearing block 32 secured, as by screws 33 to the side frame member 10. Rotation is transmitted to the crank shaft 31 by conventional means, not shown.

The lay 20 has a shuttle box, broadly designated at 36, on its outer end and since this end of the lay 20 is the end adjacent which the usual magazine and bobbin or quill transfer mechanism is mounted, the shuttle box 36 is constructed accordingly and the preferred embodiment of the invention is shown in association therewith. It is manifest that the improved picker stick check device may, with slight modifications, be applied equally as well to a shuttle box which is not especially constructed to accommodate the usual quill transfer mechanism of a loom.

The shuttle box 36 comprises a conventional right-hand lay end 37 having a plate portion 38 integral therewith which is adapted to be secured to the lay 20 in a conventional manner. The right-hand end of a conventional picker stick guide 41 is secured, as by a screw 42, to the lay end 37 (Figure 4). The left-hand end of the picker stick guide 41 is secured to the lay 20 by the bolt 26 which also secures the sword 17 to the lay 20. The picker stick guide 41 has a conventional quill chute 43 integral therewith and usually has a downwardly projecting portion 44 depending from the central portion thereof and which is adapted to assist in supporting the usual leather picker stick check strap but which, in this instance, is merely shown to illustrate that it is not necessary to remove this portion 44 when the improved picker stick check device is mounted on the loom.

The shuttle box 36 also comprises a front shuttle box plate 45 which is secured to the upper surface of the plate portion 38 of the lay end 37 as by screws 46. The shuttle box 36 has a back box plate 47, the right-hand end of which (Figure 3) is secured by a bolt 50 to the sword 17. This back box plate 47 has a back box plate extension 51 integral therewith, the left-hand end of which is secured by a bolt 52 to the lay end 37. This bolt 52 also slidably penetrates the right-hand end portion of the lay 20 in Figure 4.

The back box plate extension 51 is spaced apart from the bottom plate 38 of the shuttle box 36 by conventional means and oscillatably mounted between the back box plate extension 51 and the plate 38 is the left-hand end of a conventional binder 54. The right-hand end of the binder 54, in Figure 3, is adapted to be urged toward the near surface of the back box plate 47 when a shuttle is boxed in the shuttle box 36.

A conventional binder spring 55 is secured to the shuttle box 36, as by screws 56, and its right-hand free end, in Figure 3, bears against the rear surface of the binder 54. The shuttle box 36 has a longitudinally extending slot 60 therein (Figure 5) which is loosely penetrated by a conventional picker stick 61 which has reciprocatory movement therein by means to be later described. The upper end of the picker stick 61, in Figures 3 and 4, has a picker 63 thereon which is adapted to engage the usual shuttle, not shown, for throwing the shuttle across the lay and is also adapted to be engaged by the shuttle as the shuttle is thrown into the shuttle box 36. It is thus seen that the picker stick 61 will receive the impact of the shuttle as it is thrown across the lay.

The lower end of the picker stick 61, in Figure 1, is mounted in a conventional manner, as at 64, on the outer end of the rocker shaft 16. A lug strap 65 connects the picker stick 61 to the lower end of a conventional stirrup 66 in the usual manner, and the upper end of the stirrup 66 in Figure 1 is secured, as by a bolt 67, to a pick shaft 70. The pick shaft 70 is mounted for rocking movement on the outside of the side frame member 10. The pick shaft 70 is provided with a pick bail 71 which usually rests upon and is actuated by a conventional pick cam 72. The pick cam 72 is fixedly mounted on a conventional cam shaft 73, one end of which is rotatably mounted in a bearing block 74 secured to the side frame member 10 as by screws 75 (Figure 2).

This particular type of loom is provided with a lay guide 76 (Figures 1 and 3) which is spaced apart from the loom side frame member 10 and is mounted on bolts 77 and 78 at its front and rear ends, respectively. The bolt 77 slidably penetrates the side frame member 10 and is secured thereto as by lock nuts 81. The bolt 78 at the rear of the lay guide 76 is secured, in the same manner as the bolt 77, to a lay guide support 83, which is in turn, secured as by a bolt 84 to the loom side frame member 10. Slidably engaging opposed sides of the lay guide 76 are inner and outer lay guide followers 85 and 86 respectively. The lay guide followers 85 and 86 slidably engage the rear and front surfaces, respectively, of the sword 17, and are clampingly secured thereto as by bolts 80 (Figure 3).

The parts heretofore described are conventional parts of a loom of a type such as is manufactured by the Draper Corporation and is known as a model "XL" loom. It is to be understood, however, that this invention may be applied to any one of several types of looms. It is with these parts that this invention is adapted to be associated.

By referring to Figure 5, it will be observed that the picker stick 61 is in its outermost position, or in the position that it will occupy when the shuttle is boxed in the shuttle box 36. It will be further noted, that the picker stick 61, upon moving into the position shown in Figure 5, moves between and is frictionally engaged by a stationary friction member or check shoe 91 at one side thereof and by a spring loaded friction member or check shoe 92 at the other side thereof. These check shoes 91 and 92 may be of any desired material, however, it is preferred that they be made of a compressed fibrous material, a laminated plastic material, or, as shown in the drawings, of a hard wood material.

The stationary check shoe 91 is secured, as by screws 93, to a cast bracket 94 having an off-set upwardly extending portion 95 integral therewith which is slidably penetrated by the screw 42 for securing the bracket 94 to the picker stick guide 41. The bracket 94 also has an outwardly extending dovetailed ear 96 integral therewith which is adjustably secured to a dovetailed arm 97, this arm 97 being a conventional part of the picker stick guide 41. The arm 97 and the ear portion 96 of the bracket 94 have coinciding adjustment slots 100 therein which are slidably penetrated by a bolt 101 (Figure 6) for adjustably securing the bracket 94 to the arm 97.

The bracket 94 also has a projection 103 thereon which is threadably penetrated by an adjustment screw 104 which has a lock nut 105 threadably mounted thereon for locking the adjustment screw 104 in adjusted position. The free end of

the adjustment screw is adapted to engage the front surface of a bracket 107 secured, as by screws 108 (Figure 6), to the free end of the spring loaded check shoe 92. The adjustment screw 104 is adjusted so as to hold the free end of the check shoe 92 in a predetermined spaced relation to the stationary check shoe 91 when the picker stick 61 has moved away from between the check shoes 91 and 92.

The bracket 107 has a rearwardly and then an inwardly projecting ear 110 integral therewith which is engaged, by means to be later described, for moving the free end of the spring loaded check shoe 92 rearwardly and out of engagement with the picker stick 61. It will be observed, in Figures 5 and 7, that the spring loaded check shoe 92 is oscillatably mounted on a screw 111, there being a suitable bushing 112, secured as by a pressed fit, in the check shoe 92 and of the same vertical height as the check shoe 92. This bushing 112 is slidably penetrated by a spacing sleeve 113 of substantially greater vertical height than the bushing 112, the upper end of which bears against the lower surface of a boss portion 114 of a bracket 115. This spacing sleeve 113 is slidably penetrated by the screw 111 which is also threadably imbedded in the boss portion 114 of the bracket 115 to thus pivotally secure the spring loaded check shoe 92 to the bracket 115.

The boss portion 114 of the bracket 115 has a bore 116 therein in which is inserted one end of a torsion spring 117 which passes around the exposed upper portion of the spacing sleeve 113 a number of times and then extends outwardly along the rear surface of the check shoe 92 to thus urge the same forwardly at its free end in Figure 5 and into engagement with the picker stick 61, when it is positioned between the check shoes 91 and 92.

The bracket 115 is substantially L-shaped in cross-section and its horizontal leg is secured as by a screw 120 to the lower surface of the lay 20. The vertical leg of the bracket 115 has an inwardly extending portion 121 integral therewith, of substantially greater length than the horizontal leg of the bracket 115, and which gradually increases in height from left to right in Figure 3. The right-hand end of the portion 121, in Figure 3, is also penetrated by the bolt 26 and is thus secured to the plate portion 25 of the sword 17 by the bolt 26.

This bracket 115 has bearing portions 122 and 123 integral therewith in which a shaft 124 is oscillatably mounted. The left-hand end of the shaft 124 in Figures 3 and 5 extends beyond the bearing portion 122 of the bracket 115 and has a finger 127 adjustably secured thereon as by a set screw 128. This finger 127 extends downwardly and engages the inner surface of the ear portion 110 of the bracket 107 secured to the free end of the spring loaded check shoe 92.

Also extending downwardly from the bearing portion 122 of the bracket 115, and in substantially parallel relation to the finger 127, is a stop member 131, which is engageable by the ear 110 to prevent the free end of the spring loaded check shoe 92 from moving inwardly beyond a predetermined point in the event the adjustment screw 104 has been adjusted too far away from the rear surface of the check shoe 92.

The shaft 124 also extends beyond the bearing portion 123 of the bracket 115 and is then bent outwardly at right angles, as at 133, and has an arm 134 secured on the free end thereof as by a pressed fit. This arm 134 extends to the right 75

in Figure 6 and is slidably penetrated by a laterally bent portion of a vertically disposed link rod 136. The link rod 136 extends downwardly closely adjacent the inner surface of the loom frame member 10 and passes between the lay guide 76 and the loom frame member 10. The lower end of the rod 136 has a laterally bent portion which slidably penetrates the free end of a lever arm 140. The lever arm 140 extends rearwardly, is bent inwardly, and then rearwardly again, at right angles, and is oscillatably mounted, intermediate its end, on a pin 141 fixedly mounted in a bracket 142. The bracket 142 extends upwardly and outwardly and is secured, as by bolts 143, to the loom side frame member 10.

The bracket 140 extends rearwardly beyond its pivot point 141 and has a cam follower portion 145 integral therewith, the rearmost end of which extends downwardly and rearwardly, at an angle as at 146, for purposes to be later described. This cam follower portion 145 of the lever arm 140 is adapted to be engaged by a cam wheel 147 fixedly mounted on the cam shaft 73. The cam wheel 147 has a lobe portion 150 integral therewith which is so positioned on the cam shaft 73, relative to the high point of the conventional pick cam 72, so as to engage the cam follower portion 145 of the lever arm 140 immediately before the pick cam 72 causes the pick ball 71 to be moved upwardly in Figure 1 which, as is well known to those familiar with the art, will cause the picker stick to move toward the center of the lay and to, in turn, throw the shuttle across the lay.

Method of operation

Since the lobe 150 of the cam wheel 147 is positioned so as to engage the cam follower portion 145 of the lever arm 140 immediately before the pick ball 71 is engaged by the cam wheel 72, the spring loaded check shoe 92 will move rearwardly and thus out of engagement with the picker stick 61 at the period of operation of the loom when the shuttle is thrown out of the corresponding shuttle box. This movement of the spring loaded check shoe 92, out of engagement with the picker stick 61, is effected by the lobe 150 moving the lever arm 140 in a counterclockwise direction in Figure 1 to thus cause the link 136 to move upwardly in Figures 1, 3 and 6.

It is manifest that upward movement of the link 136 in Figure 6 will cause the shaft 124 to move in a counterclockwise direction thus moving the lower end of the finger 127 outwardly in Figure 6. Since the finger 127 is in engagement with the portion 110 of the bracket 107, secured to the spring loaded check shoe 92, this will cause the spring loaded check shoe 92 to be moved outwardly or away from engagement with the picker stick 61.

Now, immediately upon the lobe 150 of the cam wheel 147 moving beyond and out of engagement with the cam follower portion 145 of the lever arm 140, the torsion spring 117 will then overcome the weight of the various movable parts of the picker stick check and will again move the spring loaded check shoe 92 toward the stationary check shoe 91 to thus condition the check shoes 91 and 92 for reception of the picker stick 61 as the shuttle is again thrown across the lay and into the shuttle box 36. As the picker stick is moved between the stationary check shoe 91 and the spring loaded check shoe 92 it is manifest that this will cushion the impact of the picker stick and the shuttle as it is boxed in

the shuttle box 36 and the picker stick 61 will be retained by the check shoes 91 and 92 until the shuttle is further actuated for its return movement.

It is thus seen that I have provided an improved picker stick check for looms embodying means for checking the movement of the shuttle of the loom in one direction and having other means for releasing the check means, this releasing means being operable from the cam shaft of the loom and in closely timed relation to the movement of the picker stick in a shuttle throwing operation.

The portion 146 on the lever arm 140 is adapted to be engaged by the lobe 150 of cam wheel 147 when the cam shaft 73 is turned reversely, or in a counterclockwise direction in Figure 1. The cam shaft 73 is turned reversely by an operator as it is often necessary to "back-up" a loom for removing a shuttle from the lay and for many other reasons well known to those familiar with the art.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a loom having a lay and a shuttle and a picker stick for projecting the shuttle across the lay, said loom also having a cam shaft and a cam wheel thereon for controlling movement of the picker stick for projecting the shuttle across the lay, check means for the shuttle comprising a stationary check shoe and a spring loaded check shoe disposed in spaced relation to each other adjacent the path of travel of the picker stick and being engageable thereby as the shuttle is thrown against the picker stick, releasing means for the spring loaded check shoe operable through the cam shaft, said releasing means comprising an oscillatable shaft mounted interme-

diate its ends on the lay of the loom, a finger on one end of said oscillatable shaft and means on the spring loaded shoe for engaging said finger, a second cam wheel on said cam shaft and a mechanical connection between the second cam wheel on said shaft and the oscillatable shaft for transmitting movement to the oscillatable shaft in timed relation to movement of the picker stick from between the spring loaded check shoe and the stationary check shoe for moving the spring loaded check shoe out of engagement with one side of the picker stick.

2. In a structure according to claim 1, said mechanical connection between the oscillatable shaft and the second cam wheel on the cam shaft comprising a lever arm oscillatably mounted intermediate its ends, one end of the lever arm being engageable by the cam wheel on the cam shaft, a right angularly bent portion integral with the oscillatable shaft and a connecting rod extending from the free end of said lever arm to the right angularly bent portion of the oscillatable shaft, whereby, upon the high point of the second cam wheel on the cam shaft engaging the lever arm, the other end of the lever arm will be moved in such a manner as to cause the oscillatable shaft to move its associated finger outwardly and to move the corresponding spring loaded check shoe out of engagement with the picker stick.

FRANKLIN A. RITCHIE.
